UNITED STATES PATENT OFFICE.

CHARLES F. MEILINK, OF TOLEDO, OHIO.

FILING-CABINET.

1,365,523.

Specification of Letters Patent. Patented Jan. 11, 1921.

Application filed June 22, 1917. Serial No. 176,286.

To all whom it may concern:

Be it known that I, CHARLES F. MEILINK, a citizen of the United States of America, residing at Toledo, Lucas county, Ohio, have 5 invented new and useful Filing-Cabinets, of which the following is a specification.

This invention relates to features of the mounting and carrying of a member as to a support, especially for slidable withdrawal therefrom.

This invention has utility when incorporated in drawer mounting for extension from the case in sheet metal furniture filing cases.

Referring to the drawings:

15 Figure 1 is a side elevation of an embodiment of the invention in a four-drawer high sheet metal filing cabinet or case, parts being broken away;

20 Fig. 2 is a plan view of a partially withdrawn drawer from the case of Fig. 1, parts being broken away;

Fig. 3 is an enlarged section on the line III—III, Fig. 2;

25 Fig. 4 is a fragmentary perspective view of the forward end of the slide before the dog is in action;

Fig. 5 is a side elevation of the forward end of the slide with the dog withdrawn to drawer holding position; and

30 Fig. 6 is an enlarged section on the line VI—VI, Fig. 2.

The case 1 has its forward or open front side bounded by the inwardly extending flange portion or style 2 cross connected by 35 the channel portions 3 in providing the rectangular spaces to be closed by the drawer fronts 4 having the withdrawing handles 5.

Extending rearwardly along the sides of the case from near the style 2 are the carriers comprising the case engaging flange 6 of the angle bars having the inwardly projecting flange 7 providing track ways on its upper and lower faces. The forward end of the track flanges 7 have the dip 8, while the 45 rearward ends of these tracks 7 have the dip or drop sections 9.

Disposed to embrace the track 7 is the slide or channel member 10 having the wider rearward portion 11 and the thinner forward portion 12. This wider rearward portion avails of the clearance distance of the style in the case as to the drawer for width stability and greater rigidity against lateral distortion than the narrower forward portion 55 12 which in drawer withdrawal, in the out-

ward travel of the slide is sufficiently narrow to clear the style in protruding along the drawer side from the case 1.

The after or rear portion 11 of the slide 10 carries near its terminal the pin 13 upon which is freely rotatable the grooved roller 14 normally riding on the underside of the track 7. Medially of its longitudinal extent the slide 10 in its broader portion 11 carries the pin 15 upon which is loosely mounted 60 the grooved roller 16, through its supporting pin 15 propelling the slide 10 in and out of the case and having two point bearing effectiveness in traveling on the underside of the track 7 while its short radius corner 17 70 away from the case 1 crowds automatically to position along the larger radius 18 of the lower track 19 of the channel 20 mounted in the recess 21 of the lower corner of the drawer 22. Adjacent the track 19, this 75 drawer channel 20 terminates in an inwardly extending guide or flange 23 coacting with the groove of the roller 16 as well as the groove of the roller 14 to limit the lateral play of the slide as to the drawer.

80 Vertically opposing the roller 16 and loosely carried by the pin 24 in the slide portion 11 is the roller 25 contacting the track 7 directly opposite the bearing of the roller 16. This roller 25, also has two bearing 85 contacts for slide and drawer propulsion relatively at the ratio of one to two out of and back into the case 1, and it has its curved edge 17 crowding the longer radius curve 18 of the upper track 26 of the channel member 20 of the drawer 22. This track 26 terminates in the inwardly extending guide 27 90 opposing the guide 23. This guide 27 coacts with the groove of the roller 25 with some lateral play, in maintaining the slide in position as to the drawer.

95 The forward narrow portion or section 12 of the slide 10 carries near its terminus the pin 28 upon which is mounted for free rotation the narrow ungrooved roller 29 and like roller 14 is of less diameter than the grooved rollers 16, 25. This roller 29 is disposed for single track bearing on the track 26. The rear terminal roller 14 of the slide normally has but the single track bearing 100 on the track 7. In the closing travel of the drawer 22, the after bend 9 in the track 7, acts through the length of the slide 10 and the forward terminal roller 29 to tilt the 105 drawer front 4 up into easy entering clearing 110

position, and this creates a frictional holding sufficient to maintain the drawer thus closed for easy withdrawal.

In the withdrawing travel, the rear portion 11 of the slide 10 does not have any interlocking relation with the flange 7 of the case, but merely freely rides along one side thereof at one half the rate of drawer withdrawal. The terminal rollers 14, 29, 10 limit the tilt of the drawer 22 on the middle fulcrum or four-point bearing rollers 16, 25, which in their loose mounting as to the slide, and due to the coacting of the track radius curves 18, anti-frictionally fix the rocking 15 axis of the slide between this roller device pair 16, 25. Slight inequalities in metal thickness and structural variations of the tracks in this travel range are automatically cared for without any binding due to this 20 self adjusting feature of the slide propelling rollers 16, 25, maintaining relation for smooth driving at all times with the case and drawer. The bend 8 in the track 7 engages the roller 16 to stop its outward travel 25 before the widened portion 11 of the slide strikes the style 2. Forward of the closed position of the drawer 22 as to the rollers 16, 25, of the slide, the track 19, has there-across the pin 30. In the outward travel of 30 the drawer 22, the dog 31 having the pivot pin 32 is drawn from its back crowded position of Fig. 4 to which it is pushed by the drawer front 4 when closed, to its holding position of Fig. 5. This travel of the dog 31 35 is permitted by the slot 33. If it is desired to remove the drawer from assembled relation with the case, when it is withdrawn to bring the slide into position shown in Fig. 4, the head of the dog 31 may be lifted to clear 40 the pin 30 on further withdrawal of the drawer. In this lifting of the head of the dog 31, it must be over the pin 30, or the pin will strike the dog extension 34 and throw the dog out for pin engagement. When the 45 drawer is withdrawn from the slide, the slide may be readily removed from the case.

The drawer 22 is normally carried by the rollers 16, 29, with the roller 25 coacting to maintain snug relation of the after section 50 of the drawer as to the slide, the roller 29 carrying the major portion of the load as the filing drawers are normally more heavily loaded at the forward end. This downward moment from the roller 29 is directly taken 55 as upward moment by the rear slide roller 14, permitted by the loose intermediate anti-friction four point bearing device 16, 25, which further coacts with the roller 14 in taking the drawer load through the slide to 60 the case. All rocking of the drawer load through the slide as to the case is fulcrum determined by the device 16, 25.

What is claimed and it is desired to secure by Letters Patent is:

65 1. A drawer, a case therefor, and a drawer

extension providing a fulcrum between the drawer and case embodying a pair of rollers determining the axis of the fulcrum, one of which rollers has bearing coaction with the case for propelling the second roller, and 70 said second roller having simultaneous bearing coactions with the drawer and case.

2. A drawer, a case therefor, and laterally of the drawer an extension providing a fulcrum between the drawer and case embodying 75 a pair of rollers together determining the axis of the fulcrum, each of which rollers has simultaneous drawer and case bearing coactions.

3. A drawer, a case therefor, and a drawer 80 extension providing centrally of its longitudinal extent a relative drawer and slide propelling bearing support embodying a vertical pair of rollers, one of which has bearing coaction with the case and the other 85 of which has simultaneous bearing coaction with the drawer and case.

4. A drawer, a case therefor, and a slide between the drawer and case providing a multiple roller drawer-tilt bearing as to the 90 slide, one of said rollers having bearing coaction with the case and a second of said rollers having simultaneous bearing coacting with the case and drawer.

5. A drawer, a case therefor, and a drawer 95 extension between the drawer and case providing a multiple roller slide tilt bearing as to the case, one of said rollers having bearing coaction with the case and a second of said rollers having simultaneous bearing coacting with the case and drawer.

6. A drawer, a case therefor, and a drawer extension between the drawer and case providing a multiple roller tilt bearing, one of 105 said rollers having bearing coaction with the case and a second of said rollers having simultaneous bearing coacting with the case and drawer.

7. A drawer, a case therefor, and a drawer extension between the drawer and case embodying a pair of longitudinally spaced tilt limiting anti-friction rollers, and a multiple roller tilt bearing intermediate said tilt limiting rollers, one of said rollers having bearing coaction with the case and a second of 115 said rollers having simultaneous bearing coacting with the case and drawer.

8. A drawer, a case therefor, and a drawer extension between the drawer and case providing a tilt bearing in itself taking the upward moment of the extended drawer and embodying rollers, one having bearing coaction with the case and another having simultaneous bearing coaction with the drawer and case.

9. A drawer, a case therefor, and a drawer extension between the drawer and case providing a forward tilt limiting carrying roller, and rearwardly therefrom a slide sustaining anti-friction bearing in itself taking 130

drawer turning upward moments from the forward carrying roller, said tilt bearing embodying rollers, one having bearing coaction with the drawer and another having simultaneous bearing coaction with the drawer and case.

10. A drawer, a case therefor having a narrowed forward opening from which the drawer may move, and an extension slide laterally of the drawer having a forward portion movable to protrude from the case with a rearward wider portion in the case back of the narrowed opening forming portion of the case.

15. 11. A drawer, a case therefor having a narrowed forward opening from which the drawer may move, and a slide between the drawer and case having a wider rearward portion back of the narrowed opening forming portion of the case retained in the case during outward travel of the drawer and slide whereby the extended slide has lateral rigidity in its case mounting.

12. A drawer extension slide of channel form embodying a main carrying section provided with a terminal grooved roller and remote therefrom a vertical pair of grooved rollers, and a second narrower section provided with a roller oppositely disposed and remote from the first grooved roller.

13. A case provided with a track having travel limiting termini, a slide coacting with said track for travel restriction by said termini, a drawer carried by the slide and provided with a pin, and a slidably mounted dog carried by the slide for coacting with the

pin in limiting drawer withdrawal as to the slide.

14. A drawer, a case therefor, and a slide between the drawer and case provided with a dog, dog engaging means operable during slide travel for moving the dog into and out of coacting position for determining travel of the drawer as to the slide, said dog having a pivot mounting and an extension therefrom coacting when the dog is in holding engagement to preclude rocking of the dog from said engagement.

15. A case provided with a track, a slide provided with a pair of rollers coacting with said track, and a drawer having a track, said slide being provided with a second pair of rollers coacting with the drawer track, one roller of one of said pairs of rollers having a pivotal mounting in the slide as to which mounting said roller has play, said loose roller being disposed as a vertical pair with a roller of the other pair.

16. A case provided with a member providing a pair of tracks, a drawer having a pair of opposing tracks embracing the case tracks, and a slide having a pair of pivot bearings, a vertically arranged pair of rollers having play as to said bearings, said rollers coacting with the four tracks and a pair of diagonally disposed terminal rollers, one normally coacting with a case track and the other normally coacting with a drawer track.

In witness whereof I affix my signature.

CHARLES F. MEILINK.
